Primary Examiner—Gary D. Watson*Assistant Examiner*—Susan Bennett Hattan(74) *Attorney, Agent, or Firm*—Barnes & Thornburg LLP(57) **CLAIM**

The ornamental design for a lid, as shown and described.

DESCRIPTION

FIG. 1 is top side perspective view of a lid showing our new design;

FIG. 2 is a top plan view thereof;

FIG. 3 is a bottom view thereof;

FIG. 4 is a front elevational view thereof, the opposite side being a mirror image thereof;

FIG. 5 is a sectional view taken along line 5—5 of FIG. 2;

FIG. 6 is a top side perspective view of a second embodiment of the lid shown in FIG. 1;

FIG. 7 is a top plan view thereof; and,

FIG. 8 is a sectional view taken along line 8—8 of FIG. 7.

The portions of the lid shown in phantom in FIGS. 6—8 form no part of the claimed design.
